M. GROVER.
Fanning Mill.
No 17,995. Patented Aug. 11, 1857.

UNITED STATES PATENT OFFICE.

MANASSEH GROVER, OF CLYDE, OHIO, ASSIGNOR TO HIMSELF, AND H. H. SEELY, OF HUDSON, MICHIGAN.

WINNOWING-MILL.

Specification of Letters Patent No. 17,995, dated August 11, 1857.

To all whom it may concern:

Be it known that I, MANASSEH GROVER, of Clyde, Sandusky county, Ohio, have invented a certain new and useful Improvement 5 in Winnowing-Machines; and I do hereby declare the following to be a full, clear, and exact description thereof, reference being had to the annexed drawings of the same, making part of this specification, 10 and in which—

Figure 1 represents a vertical section of a winnowing machine embracing my improvement, and Fig. 2, a top view of the same.

15 In both these views the hopper is removed.

In all grain cleaning machines which I have seen one defect was most prominent, viz, the failure of the fan to impart to the screens and grain, not more than about one- 20 half of the air created by it; for, it is well known that not much more than that proportion is forced by the fan out of the case, but kept within it and carried around and around with the fan-blades. An attempt 25 has been made to obviate this defect by placing the blades of the fan obliquely in such manner as to tend constantly to force the air from the center; but I have found that even this arrangement does not force 30 out the air it creates (for the lack of compression).

Knowing therefore, that the full volume of the blast of the fan would greatly facilitate the cleaning of the grain, I endeavored to obtain it, and by actual ex- 35 periment I found that by simply arranging in the throat or opening (a) of the fan case (b) a series of air troughs or scoops (c) which extend from the case (b), that they would catch the air from the blades so as 40 to cause it to pass freely from the case, and thus prevent a large portion (as in other machines) from passing back and following the rotary motion of the fan, which it cer- 45 tainly would do if these troughs were not thus arranged, or if they were flat boards, as in the other machines. And to act in connection with the scoops (c) in effecting this desirable result, I have constructed the blades (d) of the fan, so that the plane of 50 their surface shall form an obtuse angle (e) which so acts as to force the blast directly into the scoops or troughs (c), one side of which trough being open so that the air unobstructedly passes freely to the 55 screens.

I have ascertained that however large the air passages may be through the fan case, there is but a very thin sheet of air passing outward from it and that, too, directly on the plane of the scoops or troughs. The 60 philosophy of it is that the fan-blades in their rotary motion throw the air off from the center nearly downward at the air passage of the fan case, and strike the scoops or troughs nearly in a downward direction 65 (therefore the philosophy of the scoop-shaped boards is quite obvious) and down very near to the scoops or troughs before the air becomes compressed sufficient to produce an air current having its required ve- 70 locity; and, to accomplish this compression most effectually the air must have two directions, outward and inward; the outward motion is to place the air where it can be thrown upon the scoops or troughs for com- 75 pression by the obtuse angle (e) of the fan blades. The mere outward direction from the fan case throws the current of air against too large a volume of air to produce an air current having the required velocity; 80 consequently this shape or arrangement of the fan blades is exceedingly obvious and indispensable, and does not require the scoop boards to stand as far apart as it would be supposed. 85

The bottoms of the scoops at their open side are made flat and extend a short distance from the fan case, for the purpose of directing the air upon the screens of the shoe. It will therefore be seen that it is not 90 the purpose of these troughs to divide the air into more currents, but only to act in conjunction with the obtuse angle of the fan blades to increase the blast or to obtain the benefit of the full volume and force, 95 which is created by the surface of each fan blade, by which the cleaning of the grain will not only be facilitated, but the labor of turning the machine is also much reduced, inasmuch as the fan does not require to be 100 turned near as rapidly as with those in general use.

The obtuse angles (e) of the blades (d) are formed near the outer edges thereof by making a portion (about one-fifth) of the 105 oblique blade radiate from the shaft upon which their arms (g) are mounted, and the oblique part (d) forms a tangent to a circle about half the diameter of the case, (b) and the tendency of the part (d) is to force the 110

air from the center. Yet, on trying it without the obtuse angle (e) I found that it did not give out as much blast or with as much force as it did when operating with the angular form seen in the drawings.

What I claim as my invention and desire to secure by Letters Patent, is—

Arranging in the throat or opening of the fan case a series of troughs or scoops

(c) in combination with the obtuse angles 10 (e) of the fan blades, in the manner and for the purpose herein fully described.

In testimony whereof, I have hereunto set my hand and seal.

MANASSEH GROVER. [L. s.]

Attest:

WILLIAM GRISHAM,
JOHN S. HOLLINGSHEAD.
